(57) **CLAIM**

The ornamental design for the ground penetrating radar device, as shown and described.

DESCRIPTION

FIG. 1 shows a top plan view of the ground penetrating radar device.

FIG. 2 shows a front side elevation view thereof.

FIG. 3 shows a left side elevation view thereof, the right side being a mirror image thereof.

FIG. 4 shows a back side elevation view thereof.

FIG. 5 shows a bottom plan view thereof.

FIG. 6 shows a top and right side perspective view thereof.

FIG. 7 shows a bottom and right side perspective view thereof, the reverse side being a mirror image thereof; and,

FIG. 8 shows a top and left side perspective view thereof.
